UNITED STATES PATENT OFFICE.

FRANK M. ASHLEY, OF NEW YORK, N. Y.

INKSTAND.

1,113,284.

Specification of Letters Patent.

Patented Oct. 13, 1914.

Application filed July 14, 1911. Serial No. 638,457.

To all whom it may concern:

Be it known that I, FRANK M. ASHLEY, a citizen of the United States, and a resident of New York city, borough of Brooklyn, in the county of Kings and State of New York, have invented certain new and useful Improvements in Inkstands, of which the following is a specification.

My invention relates to inkstands, and the object of my invention is to provide an inkstand which can be manufactured at a very low cost, and which will have a large ink capacity.

A further object is to provide an inkstand having a glass reservoir with a depression in the bottom thereof and which can be made of blown glass instead of pressed glass, which has heretofore been the most common type.

20 A further object is to provide the body portion having the reservoir therein, with a base portion which can be attached to the body portion after the body portion is formed, in a simple and expeditious manner, 25 by means of spring elements formed integral with said base portion, and preferably in such a manner as to provide an unbroken circular band at the top and bottom portions of said base portion.

30 Referring to the drawings which form a part of this specification, Figure 1 is a view of an inkstand shown partly in section, and embodying my invention. Fig. 2 is a view showing a modified form of base ring and 35 also embodying my invention. Fig. 3 is a fragmental detail sectional view showing a modified form of body in which the lower circumferential edge is tapered.

A, indicates the body portion which is 40 preferably made of blown glass, and comprises a reservoir A' having a central depression A², and B indicates the dip tube which extends downward to near the depression A². By reason of forming the depression A² in the reservoir A, a corresponding projection A⁴ is formed on the bottom of the body portion A.

45 By referring to Patent #830,633 granted to me on September 11th, 1906, an inkstand is therein disclosed, having its upper part made of a form very similar to the present form, but in pressed glass stands such as disclosed in the patent just referred to, the base and top portion may be made integral, 55 the depression being formed in the base portion, but in making the stand in blown glass,

it has been found impossible to make a blown glass stand having the depression and forming the base of glass and integral with the body portion.

By reason of the comparative cheapness of blown glass over pressed glass, it is desirable to provide a practical inkstand having the advantages of that referred to in the patent above mentioned, and I have conceived that the body A can be made of blown glass, and a base ring or portion, can be made which will engage the body portion and serve to support the body portion A, which on account of the projecting portion A⁴ would not otherwise rest properly on a plane surface.

In carrying out my invention I preferably provide the body portion with a circular projecting bead A⁵, but could dispense with this bead by making the lower portion of the outer wall tapered as illustrated in Fig. 3 and indicated by A⁶. The base ring C is preferably formed of thin spring metal such as brass, or from elastic fiber, and consists of a ring, preferably but not necessarily, having an unbroken circular top portion C', and a circular unbroken bottom portion C², with spring elements C³ formed integral with the ring at their lower ends and bent inwardly toward the center of the ring as illustrated, so that the body A may be inserted through the ring from below and forced upward past the spring elements C³, when the spring elements will spring back into position beneath the bottom of the reservoir as shown, to hold the body A, thus completing the construction.

Referring to Fig. 2, I have shown a better form from the standpoint of beauty of design. The base ring D is provided with unbroken circular portions D' and D² the same as the ring C, but the ring D, is formed with a portion of its body of somewhat less diameter than the diameter of the bottom of the body A, indicated by D³, and this portion is slotted by vertical slots placed close enough together to form spring elements, so that when the body A is forced upward, the spring elements are forced outward to permit the beaded ring A⁵ to pass above them into the position shown and locked in this position. By providing the base ring with the unbroken ring portions C'—C² and D'—D², the base ring will retain its form and the life of the stand will be prolonged. Cement may be placed in the bottom of the

ring if desired, to increase the weight of the base portion. By this construction I am able to provide an inkstand having a diameter of base of three inches, at a cost of less than three cents each, and having all the features of utility of my former stand referred to above which costs to provide several times this amount.

Having thus described my invention, I claim as new:

1. An inkstand comprising a bowl having a circumferential bead, a circular base therefor, the internal diameter of the upper edge being smaller than that of the bead, the upper portion of said base forming a continuous unbroken band, peripheral slits below said continuous band, the material between the slits being bent inwardly to constitute the springs adapted to spring under the bowl when the latter is inserted into the base.

2. An inkstand comprising a bowl having a downwardly projecting bottom portion, of a base consisting of a sheet metal ring having a lower internal diameter not less than the greatest diameter of the bowl and an upper internal diameter less than the greatest diameter of the bowl said ring having vertical slits, the material between the slits constituting springs, said springs being adapted to spring under the bowl when the latter is inserted into the base.

3. An inkstand comprising a bowl having a downwardly projecting bottom portion, of a base consisting of a sheet metal ring having a lower internal diameter not less than the greatest diameter of the bowl and an upper internal diameter less than the greatest diameter of the bowl said ring having vertical slits, the material between the slits constituting springs contiguous to each other, the bottom portion of the ring presenting a continuous unbroken band.

4. An inkstand comprising a bowl having a lower central enlargement and a peripheral bead, of a base consisting of a sheet metal ring having a continuous outer surface consisting of contiguous springs, and a contracted upper portion adapted to engage the bead, said springs being adapted to snap under the bowl and coöperate with said contracted portion and said bead to retain the bowl in place.

5. An inkstand comprising a bowl having a central downwardly projecting portion and an annular bead, of a base consisting of a ring having a continuous upper portion of a less diameter than the diameter of the bead and a continuous lower portion of a diameter not less than the diameter of the bead, and vertically extending integral springs adapted to snap under the bowl and coöoperating with the bead and the upper portion of the ring to hold the bowl in place,

said springs forming a continuous outer surface.

6. An inkstand comprising a blown glass bottle having a central downwardly projecting portion, a base ring having its top circular edge portion formed in an unbroken band and of less diameter than the bottom of the bottle, and having spring elements formed integral therewith and located below said unbroken upper portion and adapted to spring under the bottom edge of the bottle to clamp and support same in position, and having an unbroken circular band portion located below said spring elements.

7. An inkstand comprising a blown glass bottle having a central downwardly projecting portion, a base ring having its top circular edge portion formed in an unbroken band and of less diameter than the bottom of the bottle, and having spring elements formed integral therewith and located below said unbroken upper portion, said spring elements being formed by curving the ring inward near its middle portion and dividing the curved portion by forming slits therein to provide a plurality of said spring elements, and adapted to spring under the bottom edge of the bottle to clamp and support same in position.

8. A base comprising a sheet metal ring having a top portion provided with an over-turned edge, and a bottom portion having an opening of greater diameter than said top portion, said top and bottom portions being united by a series of inwardly bent integral springs contiguous to each other throughout their length and presenting a substantially continuous outer surface, said springs being adapted to snap under a member to be supported on said base.

9. An inkstand comprising a bowl and a base, the interior diameter of the upper edge of the latter being less than the greatest diameter of the bowl, the upper portion of the base forming a continuous unbroken band, and the lower portion having an internal diameter which is greater than the largest diameter of the bowl and forming a continuous unbroken band, and a plurality of slits intermediate said bands, the material between the slits being bent inwardly, so as to form a resilient retaining means bearing against the bottom of the bowl to fix the latter securely within the base, but permitting its ready removal therefrom.

Signed at New York city, in the county of New York and State of New York this 8th day of July A. D. 1911.

FRANK M. ASHLEY.
